PITCH CHANGING DEVICE FOR MUSICAL INSTRUMENTS

Filed Dec. 5, 1947

UNITED STATES PATENT OFFICE

2,487,193

PITCH CHANGING DEVICE FOR MUSICAL INSTRUMENTS

Walter E. Smith, Ventura, Calif.

Application December 5, 1947, Serial No. 789,857

7 Claims. (Cl. 84—312)

1

This invention relates to musical instruments and is particularly directed to improvements in devices for changing the pitch of a string. Devices of this type are employed in instruments of the lute type, as for example, a guitar.

In my co-pending application, Serial No. 740,760, filed April 11, 1947, I have shown a pitch changing device for a guitar, which device is adapted to be leg operated. The purpose of that device is to enable a musician to change the pitch of a string on the instrument from time to time during the rendition of a single musical composition in order that the various chords required may be readily available without slanting the "steel" which is employed by the musician in the customary fashion. While that device is admirably suited to the requirement of changing pitch repeatedly during the rendition of a single musical composition, it is not practical to use the conventional music for guitars when operating such device. This is true because standard guitar music used universally in teaching students to play the guitar requires that the strings of the guitar be tuned in a certain predetermined relationship, and that this relationship remain unchanged while the particular composition is being played. Symbols are marked for each measure in the musical score, and these symbols indicate the required position of the "steel" for producing the desired chords in the musical composition.

Conventional guitar music ordinarily includes a statement of the required tuning on the first sheet of each musical composition. Because of the limitations of steel guitar tuning, one musical composition may be played more effectively in one tuning pattern than in another. Two standard tunings have been accepted, and these are most popular for both students and professionals and are most widely used. These two tunings differ only by a full tone change on one string. Accordingly, when a musician is about to play a musical composition he first checks to see which of these two standard tunings is required, and if necessary adjusts the particular string to the proper position. The pitch of the string is not changed throughout the entire musical composition. When another composition is to be played the musician again checks, and if the standard tuning is the same no changes need be made, whereas the tension of the string may be returned to its original condition if the other tuning is to be employed. Conventional guitars and guitar-like instruments are conventionally provided with individual tuning knobs which may

2

be gear operated, and the task of changing from one pitch to another requires careful adjustment of such knobs in order that the pitch shall be exactly that which is desired. It is distracting for both audience and musician when the latter must pause in a guitar concert to stop and retune to the desired tuning pattern for the next musical rendition.

Accordingly, it is the principal object of the present invention to provide a pitch changing device for a string or strings of a musical instrument which is preadjusted so that the pitch of the string may be changed from one tone to another in rapid fashion without requiring any careful or critical attention by the musician.

Another object is to provide a string tensioning plunger provided with adjustable stop means and adapted to be actuated by a lever acting through a resilient element.

Another object is to provide a novel form of latch means for holding the actuating lever in position.

Another object is to provide a pitch changing device for the strings of a musical instrument which is mounted in a manner to avoid interference with the normal operation of playing the instrument, and which is simple and rugged in design, economical to manufacture on a quantity basis, and adapted for mounting on a musical instrument in a manner to avoid defacement or mutilation thereof.

Other objects and advantages will appear hereinafter.

In the drawings:

35 Figure 1 is a top plan view of a steel guitar having attached thereto a pitch changing device embodying my invention.

35 Figure 2 is a side elevation of the right-hand end of the guitar shown in Figure 1 and illustrating the attachment embodying my invention.

Figure 3 is a transverse sectional view taken substantially on the lines 3—3 as shown in Figure 2.

Figure 4 is a longitudinal sectional view taken along the string engaged by the pitch changing device.

Figure 5 is a view of the underside of that portion of the guitar shown in Figure 2.

Referring to the drawings, the musical instrument generally designated 10 may be a standard guitar or a steel guitar, or any one of a number of conventional guitar-like instruments. A series of strings 11 is secured to the body 12 at one end 13 and extend between the usual bridge 14 and the nut 15. A shield 16 may extend over

the strings 11 to provide a hand rest if desired. The other end of each of the strings is spooled about a pin 17 extending through the neck head 18 and provided with a gear wheel 19 on its lower end. Each of the gear wheels 19 is adapted to be engaged by a worm pinion (not shown) mounted on the shaft of the tuning knob 20. The pitch of each of the strings 11 is tuned by rotating one of the tuning knobs 20. The only change required when changing from one standard form of tuning to the other standard form is to change the pitch of the string 11a one whole tone. This is ordinarily accomplished by suitable manipulation of the knob 20a. Such manipulation, however, requires the very careful attention of the musician in order that the pitch may be exactly that desired, for any error in setting this adjustment will cause the instrument to sound slightly off-key and will spoil the harmony of the chords.

In accordance with my invention, I provide a plunger 21 slidably mounted within a bore 22 provided in the nut head 18 at a location beneath the string 11a and between the nut 15 and the pin 17a. The top of the plunger 21 is provided with a groove 23 for reception of the string 11a. Movement of the plunger 21 in a direction toward the string 11a serves to increase the tension in the string and change its pitch.

A base member 24 is secured to the underside of the nut head 18 by any convenient means such as the attaching screws 25, and is provided with parallel downwardly extending side members 26 and 27 connected by a bottom plate 28. A pair of stationary transverse pins 29 and 30 extend across the base 24 between the side members 26 and 27 in parallel relationship. The plunger 21 extends downwardly through the bore 22 and aligned openings 31 and 32 provided in the base 24. An actuating lever 33 having an aperture 34 is provided for moving the plunger 21 to tension the string 11a. As shown in Figure 4 the plunger 21 extends through the aperture 34 and a resilient coil spring 35 encircles the plunger 21 and extends between the washer 36 on the lever 33 and the shoulder 21a provided on the plunger 21. The actuating lever 33 normally rests on the transverse pins 29 and 30 but may be raised to the position illustrated by the dotted lines in Figure 4 to cause the plunger 21 to move toward the string 11a. The extent of such movement is limited by the engagement of the adjustable stop member 37 with the underside 38 of the base 24. The adjustable stop member 37 is provided with internal threads cooperating with the external threads 21b provided on the lower end of the plunger 21.

A relatively heavy return spring 39 is confined between a shoulder 40 on the element 37 and the surface 38 on the body 24. When the actuating lever 33 is raised it pivots about the transverse pin 29, compressing the springs 35 and 39 to raise the plunger 21. The precise angle of arcuate travel of the actuating lever 33 is unimportant since the motion of the lever 33 is communicated to the plunger 21 by way of the spring 35, and in any event the upward motion of the plunger 21 is limited by engagement of the element 37 with the body 24. Accordingly, once the element 37 is adjusted to the correct position on the plunger 21, movement of the actuating lever 33 sufficient to bring the element 37 into contact with the body 24 results in changing the pitch of the string 11a exactly one tone.

Latch means are provided for maintaining the actuating lever 33 in its upper position, and as

shown in the drawings this latch means includes slot 41 having a lateral extension 41a formed in the end of the shield 44. The lever 33 is moved to its latched position by raising it within the slot 41 and then swinging it laterally about the plunger 21 into the extension 41a. The springs 35 and 39 hold it in frictional contact with the edge of the slot extension 41a, and hence prevent its accidental displacement. It will be understood that the aperture 34 in the actuating lever 33 and the opening in the washer 36 are sufficiently large to accommodate the pivotal movement of the actuating lever 33 with respect to the plunger 21. Furthermore, the aperture 34 acts as a pivot point around which the lever 33 is shifted when it is to be shifted into the notch 41a.

The shield 44 is provided to enclose the major portion of the mechanism of the device and to provide an ornamental appearance. An opening 45 is provided in the lower portion of the shield to receive the spring 39, plunger 22 and adjustment stop 37. The shield 44 may be supported in any convenient manner such as, for example, by the screw element 46 which attaches it to the side member 26 of the body 24.

In the operation of my device the guitar is tuned to one of the standard tuning patterns with the lever 33 in its inoperative position as shown in Figure 4. The lever 33 is then moved to the dotted line position illustrated in Figure 4 and latched in place. The adjustable stop member 37 is then turned relative to the plunger 21 until the pitch of the string 11a corresponds exactly to the desired pitch for the second form of standard tuning pattern. Thereafter, the musician need only move the actuating lever 33 to its latched position, or release it to permit it to take the position shown in Figure 2, depending on the tuning pattern indicated by the music. It is thus unnecessary to make any careful or critical tuning adjustments when changing from one standard tuning to the other. The device is out of the way so that it does not interfere with normal playing of the instrument and does not mar the instrument or deface it in any way. It is recognized that the above described device may be adapted for changing other tuning patterns by operating on another string or combination of strings.

Having fully described my invention, it is to be understood that I do not wish to be limited to the details herein set forth, but my invention is of the full scope of the appended claims.

I claim:

1. A device for changing the pitch of the string of a musical instrument, comprising in combination: a base member; a string-engaging plunger element slidably mounted relative to the base member; an actuator pivotally associated with the base member; a resilient element interposed between the plunger and said actuator, whereby pivotal movement of the actuator serves to move the plunger in a direction to change the tension in the string; and stop means independent of the actuator adapted to limit the travel of the plunger.

2. A device for changing the pitch of the string of a musical instrument, comprising in combination: a base member; a string-engaging plunger element slidably mounted relative to the base member; an actuator pivotally associated with the base member; a coil spring encircling a portion of the plunger and adapted to be engaged by said actuator, whereby pivotal movement of

the actuator serves to cause the spring to move the plunger in a direction to change the tension in the string; and means including a stop element adjustably mounted on the plunger adapted to limit travel of the plunger.

3. A device for changing the pitch of the string of a musical instrument, comprising in combination: a base member; a string-engaging plunger element slidably mounted relative to the base member; a lever pivotally associated with the base member; a coil spring encircling a portion of the plunger and adapted to be engaged by said lever, whereby pivotal movement of the lever serves to move the plunger in a direction to change the tension in the string; and a stop element on the plunger adapted to engage the base member before the lever reaches the end of its path of travel.

4. A device for changing the pitch of the string of a musical instrument, comprising in combination: a base member; a string-engaging plunger element slidably mounted relative to the base member; a lever pivotally associated with the base member; a coil spring encircling a portion of the plunger and adapted to be engaged by said lever, whereby pivotal movement of the lever serves to move the plunger in a direction to change the tension in the string; a stop element on the plunger adapted to engage the base member before the lever reaches the end of its path of travel; and a return spring adapted to resiliently urge the plunger toward its inoperative position.

5. A device for changing the pitch of the string of a musical instrument, comprising in combination: a base member secured to the instrument; a plunger slidably mounted with respect to the base and adapted to engage the string; an actuator having an aperture therein adapted to receive the plunger therethrough, whereby the actuator may swing laterally with respect to the plunger; means on the base providing a pivotal mounting for the actuator; a spring operatively interposed between the actuator and the plunger, whereby pivotal movement of the actuator is effective to move the plunger with respect to the base; and a latch for the actuator engageable through swinging movement of the actuator about the plunger and adapted to maintain the actuator in operative position.

6. An attachment for a musical instrument having a string extending between a nut and an anchoring device, comprising in combination: a base member secured to the instrument; a plunger slidably mounted with respect to the base and being grooved to engage the string; an actuator having an aperture therein adapted to receive the plunger therethrough, whereby the actuator may swing laterally with respect to the plunger; means on the base providing a pivotal mounting for the actuator; a spring encircling the plunger and operatively interposed between the actuator and the plunger, whereby pivotal movement of the actuator is effective to move the plunger with respect to the base; and a latch for the actuator engageable through swinging movement of the actuator about the plunger and adapted to maintain the actuator in operative position.

7. An attachment for a musical instrument having a string extending between a nut and an anchoring device, comprising in combination: a base member secured to the instrument; a plunger slidably mounted with respect to the base and adapted to engage the string; an actuator having an aperture therein adapted to receive the plunger therethrough, whereby the actuator may swing laterally with respect to the plunger; means on the base providing a pivotal mounting for the actuator; a spring operatively interposed between the actuator and the plunger, whereby pivotal movement of the actuator is effective to move the plunger with respect to the base; a stop element on the plunger adapted to engage the base member before the actuator reaches the end of its travel; and a latch for the actuator engageable through swinging movement of the actuator about the plunger and adapted to maintain the actuator in operative position.
